(57) **CLAIM**

The ornamental design for a plug in insect trap with adhesive fan, substantially as shown and described.

DESCRIPTION

FIG. 1 is a front and right side isometric view of a plug in insert trap with adhesive fan according to the present invention;

FIG. 2 is a rear and left side isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are for illustrative purposes and represent environmental structure and unclaimed portions of the invention and therefore form no part of the claimed design.
